ABSTRACT OF THE DISCLOSURE

A label for belts to be secured to a belt loop. The tag or label may be made of leather and has self locking characteristics to allow it to be placed around a belt loop and attached thereto. The tag has identical containing areas for the display of price and other trade indicia.

This invention relates to indicia carrying attachments for use in the display of merchandise and, more specifically, to a tag-like attachment suitable for use in conjunction with the display of belts and other products.

In displaying belts or other merchandise for sale, price and similar information is commonly displayed on a tag or label attached directly to the product. Such attachments must be fastened in a secure manner so as to permit storage and handling and must be easily removable without causing damage to the merchandise. The attachment must provide an adequate area for printed matter and should maintain its orientation so that the printed matter is readily visible. Prior attachments for belts include, for example, printed cardboard tags attached to the belt by a length of string and printed foil sheets folded around the belt ring. However, string tags tangle easily when belts are displayed hanging adjacent to one another, and foil tags present a less than desirable appearance and are limited in size by the size of the belt loop. The present invention overcomes these prior faults and permits price and other information to be displayed on a tag securely attached to a product such as a belt in a manner so as to be readily removable without causing damage to the product and to provide a large attractive area for printed matter which will maintain its orientation and thus be readily visible. Furthermore, a tag in accordance with the invention provides a rich appearance which has been found to be important in the sale of items such as men's belts.

In accordance with the invention, price or other indicia is inscribed upon a strip of flexible material shaped to be easily attached to a belt loop or other loop-like element of a product to be displayed. The flexible strip is cut to include a broad primary indicia carrying portion and an adjacent apertured portion, which may include a single selectively dimensioned nearly rectangular aperture. Above the apertured portion the strip is shaped to include a narrow necked-down portion and a broad tab-like locking portion both dimensioned in accordance with the dimensions of the aperture in the apertured portion so that in affixing the strip to a piece of merchandise the narrow portion can be easily passed through the apertured portion while the broad portion engages the apertured portion. Above the broad tab-like locking portion the strip includes a secondary indicia carrying portion, also selectively dimensioned in accordance with the size of the aperture, and two secondary locking tabs which protrude outward from the sides of the secondary indicia carrying portion. In securing the strip to a belt or other article, the narrow portion is threaded through the apertured portion, the secondary indicia carrying portion is brought into alignment with the primary indicia carrying portion and the tabs are inserted into the apertured portion thus main-

2

taining the secondary indicia carrying portion in proper alignment and forming a secure connection.

The invention will be fully apprehended from the following description of an illustrative embodiment thereof taken in conjunction with the appended drawings wherein:

5 FIG. 1 is a front view of a strip of flexible material dimensioned in accordance with the invention and suitable for use in conjunction with the display of belts and other similar products.

10 FIG. 2 is a sectional view taken along the center line of the strip shown in FIG. 1.

15 FIGS. 3, 4, 5 and 6 show a tag constructed in accordance with the invention and the buckle section of a belt during progressive stages in the process of attaching the tag to the belt.

FIG. 7 is an end view, partially in section, of the tag and belt loop of FIG. 6, with the cross-sectional portion being taken along line 7—7 in FIG. 6.

FIG. 1 shows a strip of flexible material shaped in accordance with the invention for use as a price tag on belts or similar products. While this tag may be constructed of any suitable flexible material, it has been found that a strip of leather approximately $\frac{1}{16}$ inch thick provides sufficient flexibility for easy attachment to a belt guide and sufficient resiliency to maintain a secure connection once the tag has been affixed. The use of leather, which is made possible by the tag's construction, provides a rich appearance and rich feel both of which are desirable for the merchandising of quality men's belts. Additionally, such leather can be easily cut and stamped with an appropriate legend; in FIG. 1 a price has been stamped on the primary indicia carrying portion 10 of the tag, and a figure has been incorporated into the tag's shape.

20 The bottom or primary indicia carrying portion 10 of the strip of material shown in FIG. 1 may be cut into any convenient shape or size according to the printed matter to be displayed on the tag. Immediately above this primary indicia carrying portion, the strip includes an apertured portion 12 which extends from the principal indicia carrying portion 10 to a narrow necked-down portion 14. The apertured portion 12 may include a solid structured section 13 located above a single aperture 11. This aperture may be in the form of a lengthwise approximately rectangular slot as shown in FIG. 1 which may be slightly wider at its center than at its ends to permit easy attachment of the tag. If this configuration is employed, only two thin leg members 19 and 20, remain between the primary indicia carrying portion of the tag 10 and the remainder of the tag. The width of the slot or the distance 25 between the thin leg members at their top and bottom ends, 11a and 11b respectively, is selected in accordance with the size relationships of other portions of the tag as discussed below. Further, this section of the strip is dimensioned in accordance with the nature and dimensions of the product to which the tag is to be attached; in the case of a belt, the structural section 13 must be narrow enough to fit within the belt ring to which the tag will be attached. It is to be understood that other configurations of apertures could be employed, and that the 30 apertured portion 12 may take on other configurations in accordance with the arrangement of apertures employed.

25 Adjacent to the structural section 13, the strip is formed into a narrow, necked-down portion 14 which is dimensioned so that its width is just smaller than the width of the edge 11b of the aperture 11 adjacent to the portion 10. The height of the narrow necked-down portion is such that the distance from the base of aperture 11 at 11b to the top of the narrow necked-down portion 14 is sufficient 35 to make one complete circle about the belt ring to which the tag is to be attached.

Above the narrow, necked-down portion 14, the strip is formed into a broad tab-like locking portion 15 dimensioned such that its height is small as compared with the height of aperture 11 and such that its width is much greater than the width of aperture 11.

A secondary indicia carrying portion 16 is located above the broad tab-like locking portion 15. This secondary indicia carrying portion includes two supplemental locking tabs 17 and 18 protruding out from its two lateral sides at a point above the broad tab-like locking portion such that the distance from the upper edges of tabs 17 and 18 to the lower edge of the broad tab-like locking portion 15 is smaller than the length of aperture 11. The width of the secondary indicia carrying portion is approximately equal to the width of the slot 11. As will be seen, this permits supplemental locking tabs 17 and 18 to be inserted in aperture 11 below the narrow leg members 19 and 20 with the broad, tab-like locking portion overlying the leg members 19 and 20 so as to maintain the secondary indicia carrying surface 16 in alignment with the primary indicia carrying surface 10 and thus provide a secure connection and a substantial area for printed matter.

The several stages in the process of attaching the tag shown in FIG. 1 to the loop of a belt are illustrated in FIGS. 3, 4, 5 and 6. In FIG. 3 a tag 30 is shown adjacent to the belt loop 31 of belt 32; the face or information bearing side of the tag is facing the body of the belt with the lower or primary indicia carrying portion 10 of the tag closest to the belt buckle. As indicated by arrow 34 in FIG. 3, the tag is then threaded through the belt loop. Clearly, with the tag dimensioned as shown in FIG. 3, the tag may be drawn into the belt loop from either side of the loop. The tag is then located within the belt loop so that the aperture 11 is just beyond the loop 31 towards the buckle 33 and, the solid section of the apertured portion 13 of the tag is under the loop. The primary indicia carrying portion of the tag 10 and the apertured portion of the tag which protrudes from the belt loop are then folded up and away from the body of the belt and back toward the remainder of the tag as indicated by arrow 35 in FIG. 3.

The secondary indicia carrying portion 16 of the tag is then folded over the belt loop into approximately the position in which it is shown in side, sectional view in FIG. 4 and in front view in FIG. 5. The primary indicia carrying portion 10 of the tag is then folded over the belt loop 31 and over the secondary indicia carrying portion 16 of the tag to the position in which it is shown in FIGS. 4 and 5. The secondary indicia carrying portion 16 of the tag and the broad tab-like locking portion 15 of the tag are then drawn through aperture 11 until the bottom of the broad tab-like portion and part of the narrow necked-down portion 14 are through the aperture. The narrow portion is then permitted to withdraw back through the aperture until the broad tab-like portion 15 engages the bottom 11b of the aperture as shown in FIG. 6. The secondary indicia carrying portion 16 is then brought into approximately parallel relation with the primary indicia carrying portion, and the secondary locking tabs 17 and 18 are inserted through the aperture to be held in place under leg members 19 and 20.

With the tag fastened in this manner, a secure attachment to the belt is achieved without injuring the belt in any way. A large printable surface is provided by the primary indicia carrying portion which may be of any desired dimension and by the secondary indicia carrying portion. The tag is maintained flush with the body of the belt for easy storage, handling, and display and so that the legend on the tag is clearly visible when the belt is

hung on the normal display rack or handled by a customer. As in the example shown in FIG. 1, the printed matter on the primary indicia carrying portion and on the secondary indicia carrying portion may be coordinated to provide a single unified message.

FIG. 7 shows the tag attached to a belt loop in partial sectional view along line 7 in FIG. 6. Thus, in FIG. 7, the solid structural section of the strip 13 is located below the belt loop 31 while the secondary locking tabs 17 and 18 are secured beneath the leg members 19 and 20 respectively. The broad tab-like locking portion 15 is located in front of the leg members 19 and 20.

It is to be understood that the above described arrangements are merely illustrative of the application of the principles of the invention. Other arrangements may be devised by those skilled in the art without departing from the spirit and scope of the invention.

What is claimed is:

1. An indicia carrying attachment which comprises a length of flexible material including a broad primary indicia carrying portion, an apertured portion adjacent to said primary indicia carrying portion, a relatively narrow necked-down portion contiguous with said apertured portion and away from said primary indicia carrying portion, said narrow necked-down portion being selectively dimensioned so as to pass freely through said apertured portion, a broad locking portion contiguous with said narrow necked-down portion, said locking portion being dimensioned so as to engage said apertured portion, a secondary indicia carrying portion contiguous with said locking portion and a plurality of supplemental locking tabs extending outward from said secondary indicia carrying portion.

2. An indicia carrying attachment as defined in claim 1 wherein said apertured portion comprises a solid structural section immediately adjacent to said narrow necked-down portion and two thin leg members intermediate said solid structural section and said primary indicia carrying portion, said leg members being substantially parallel to one another and the distance between said leg members at the point where said leg members meet the primary indicia carrying portion being slightly greater than the width of said narrow necked-down portion and smaller than the width of said broad locking portion; wherein said secondary indicia carrying portion is of a width approximately equal to the distance between said thin leg members; and wherein said broad locking portion is of a width greater than the distance between said thin leg members, so that said indicia carrying attachment may be fastened to a belt loop with said solid structural section underlying said belt loop, and said secondary indicia carrying portion superimposed upon said thin leg members with said broad locking portion overlying said leg members, and said supplemental locking tabs underlying said leg members.

3. An indicia carrying attachment as defined in claim 2 wherein said flexible material is leather.
